(No Model.)

K. W. OTTSTADT & R. WIRTH.
SAW.

No. 469,172.

Patented Feb. 16, 1892.

UNITED STATES PATENT OFFICE.

KARL W. OTTSTADT, OF KOSTHEIM, AND RICHARD WIRTH, OF FRANKFORT, GERMANY.

SAW.

SPECIFICATION forming part of Letters Patent No. 469,172, dated February 16, 1892.

Application filed October 2, 1889. Renewed September 24, 1891. Serial No. 406,757. (No model.) Patented in Germany August 19, 1889, No. 51,932; in Switzerland August 20, 1889, No. 1,375; in France August 23, 1889, No. 200,367; in England August 26, 1889, No. 13,449; in Belgium March 10, 1890, No. 89,786, and in Austria-Hungary January 30, 1891, No. 41,344 and No. 67,598.

To all whom it may concern:

Be it known that we, KARL W. OTTSTADT, of Kostheim-on-the-Main, and RICHARD WIRTH, of Frankfort-on-the-Main, Germany, both subjects of the Emperor of Germany, have invented a new and useful Improvement in Saws, (for which we have obtained Letters Patent in the following countries: in England, No. 13,449, dated August 26, 1889; in Germany, No. 51,932, dated August 19, 1889; in Switzerland, No. 1,375, dated August 20, 1889; in France, No. 200,367, dated August 23, 1889; in Belgium, No. 89,786, dated March 10, 1890, and in Austria-Hungary, No. 41,344 and No. 67,598, dated January 30, 1891,) of which the following is a specification.

This invention relates to saws for cutting angled or curved lines, as in slotting, recessing, dovetailing, &c., the transverse section 20 of which saws is bent or curved to conform to that of the bent line to be cut and gradually enlarges from nothing at one end to the full size of the final cut at the other. These saws have heretofore been made single—that is, to 25 cut the bent line by starting at one end and finishing at the other—necessitating a construction of saw which was weak and liable to distortion when in use.

The object of our improvement is to provide 30 a saw for such purposes which will cut the slot or recess simultaneously from both ends of the bent outline of the same toward the middle, by which any form of slot or recess may be cut by a single stroke, and a strong 35 and symmetrical construction of saw is obtained.

The invention consists of a double saw of novel and peculiar construction, substantially as hereinafter described and claimed.

Reference is to be had to the accompanying 40 drawings, forming part of this specification, in which—

Figure 1 represents a blank from which a saw embodying our invention is made. Fig. 2 is a side elevation of the said saw. Figs. 3, 4, 5, 6, 7, 8, and 9 are transverse sections of the said saw on the lines $x x$, $y y$, $z z$, $v v$, $w w$, $r r$, and $s s$, respectively.

The contour of the slot or recess to be cut, as in the edge of a board, being the same as 50 the part of the saw-section (shown in Fig. 9) indicated by the letters $b c d e f g$, the blank shown in Fig. 1 is formed of sheet or plate steel of a width equal to the total length of the contour $b c d e f g$ plus sufficient to form 55 two non-cutting blade-bodies $a h$ and divided medially, as from the lower end to within a short distance of the other end, thereby forming two separate blades A B, integrally united, as at the upper end. The 60 upper and lower ends of each blade are extended to form perforated lugs $A' A^2$ and $B' B^2$ for attachment to the saw-holder. Lines of teeth are cut on the inner edge of each blade, converging from the inner edges of the blade-bodies $a h$, as at the lower ends, to a meeting 65 at the upper ends, or preferably, as shown in Fig. 3, the line of teeth on one blade is extended past the end k of the line of teeth on the other, a space p being left for clearance. 70 The whole blank is then bent transversely, so as to conform at every cross-section to the surface of a general cylinder having the cross-section $a b c d e f g h$, as shown in Fig. 9, the blade-bodies $a h$ being by preference in parallel planes and all the longitudinal elements 75 of the blades and bodies, so far as they extend, being parallel to each other, as shown in Fig. 1. Where the toothed edge takes a sharp turn, as at l , a gap is preferably left to avoid 80 cutting at different angles at the same time.

In operation the divided initial ends of the separate blades A B are brought simultaneously against the two terminals of the outline of the proposed slot, corresponding to the 85 saw-section $b c d e f g$, and the saw then drawn downward, when the parts of the slot outline corresponding to the parts b and g , c and f , and d and e of the saw-section will be cut in such pairs in succession, a single downward 90 stroke generally completing the entire slot, although in some cases a reciprocatory but gradually progressive motion of the saw may be necessary.

It is evident that double saws of this description may be made to cut on any desired 95

outline, while, being symmetrical and evenly sustained at all points, they are not liable to distortion or breakage.

We claim as our invention—

- 5 A saw formed with two toothed blades, which are separated laterally at one end and united at the other end, the lines of teeth of which blades converge from the divided end to a meeting or overlap at the other end, and
10 the blades bent transversely to conform at

all points to the surface of a general cylinder, substantially as described.

In testimony whereof we have signed our names to this specification in the presence of two subscribing witnesses.

KARL W. OTTSTADT.
RICHARD WIRTH.
